UNITED STATES PATENT OFFICE.

FREDERICK W. SCHOEN, OF SCRANTON, PENNSYLVANIA.

EGG-CRATE.

1,109,873.

Specification of Letters Patent. Patented Sept. 8, 1914.

Application filed May 8, 1913. Serial No. 765,946.

To all whom it may concern:

Be it known that I, FREDERICK W. SCHOEN, a citizen of the United States, residing at Scranton, in the county of Lackawanna and 5 State of Pennsylvania, have invented certain new and useful Improvements in Egg-Crates, of which the following is a specification.

This invention relates to improvements in 10 containers, more particularly to shipping crates for eggs, fruit, and other commodities, and which are usually supplied with a sliding cover, and has for one of its objects to provide a simply constructed attachment 15 whereby the sliding cover is secured in place and effectually protects the contents of the container, while at the same time enabling the cover to be readily detached and attached when required.

20 With these and other objects in view the invention consists in certain novel features of construction as hereinafter shown and described and then specifically pointed out in the claims, and in the drawings illustrative of the preferred embodiment of the invention.

Figure 1 is a perspective view of one of the improved receptacles or crates with the sliding cover partly removed and with the 25 improved attachment connected therewith. Fig. 2 is an enlarged sectional detail illustrating the manner of arranging the automatic catch for the end of the cover. Fig. 3 is a sectional detail illustrating the manner 30 of arranging the spring catch for the central portion of the cover. Fig. 4 is a perspective detail illustrating the construction of the rear corner of the cover.

Corresponding and like parts are referred 40 to in the following description and indicated in all the views of the drawings by the same reference characters.

The body of the improved crate is represented as a whole at 10 of the usual form 45 and preferably provided with a central partition 11 to divide the interior into two compartments. At the ends the body 10 is provided with cleats 12-13 which overhang the body for a distance and provided with 50 guideways for the cover 14. The cover is preferably provided with cleats 15-16 at the ends which bear at their outer edges against the inner faces of the body cleats 12-13. By this means the cover 14 may be 55 inserted in position over the body 10 and

completely closes the latter, and corresponds in area with the upper area of the body. One of the body cleats, for instance the cleat 13, is provided with a longitudinal recess 19 having an oblique inner portion over 60 which a plate 17 is disposed, the plate being provided with an aperture 18 at its inner end. The apertured end of the member 17 is flush with the inner face of the portion of the cleat 13 against which the adjacent cover 65 cleat, as for instance the cleat 16, bears as represented in Fig. 2.

Formed in the face of the cleat 16 next to the cleat 13 is a longitudinal recess 19', and pivoted at 20 within the recess 19' is a 70 finger 21 having an off-set 22 at its inner end to engage in the opening 18 of the plate 17 when the cover is disposed in its closed position. At its outer end the finger 21 projects beyond the outer terminal of the recess 19' as represented at 23, against which the finger of the operator may be pressed to release the member 21. A spring 24 is located within the recess 19' and bears constantly against the inner terminal of the 75 member 21 and thus maintains the projection 22 yieldably within the opening 18 when the cover 14 is in closed position. The inclined portion of the plate 17 forms a guideway over which the projection 22 80 passes when the cover 14 is forced into closed position to cause the member 21 to be automatically engaged with the plate 17 and thus lock the cover in its closed position. By this arrangement it will be obvious 85 that it is not necessary to manually actuate the member 21 when closing the cover 14. At their inner ends the cleats 12-13 are provided with stop blocks 25 against which the inner edges of the cover 14 bear to limit the 90 inward movement of the latter, the adjacent corners of the cover being recessed, as represented at 26, to bear over the stop blocks so that the rear edge of the cover 14 bears upon the upper edge of the back of the 95 body 10.

Formed in the forward edge of the cover 14 is an opening or a notch 27 in which a spring catch 28 is secured at 29 and provided with a depression 30 adapted to engage in a cavity 31 in the upper edge of the partition 11, the inner side of the depression 30 being inclined so that when the cover is moved inwardly the catch will be automatically elevated and pass over the front of the 100 105 110

body 10 and automatically engage in the cavity 31 when the cover is fully closed. By this means the central portion of the cover is supported and prevented from displacement. By this arrangement also the cover is held at two points so that its security is increased.

Having thus described the invention, what is claimed as new is:

- 10 1. A container having upwardly directed guide cleats with a channel in the inner face of one of the cleats, the inner end of the channel being oblique to the transverse plane of the container and merging gradually into the inner face of the cleat and with a socket at the inner end of the oblique portion, a cover slidably engaging the guide cleats, and a spring controlled catch device carried by the cover and including a projection for en-
- 15

gaging the oblique portion of the channel 20 and guided thereby into the socket.

2. A container having upwardly directed guide cleats with a channel in the inner face of one of the cleats and a socket at the inner end of the channel, a cover slidably engaging the guide cleats, a cleat carried by the cover and having an outwardly opening channel, and a spring controlled catch device mounted to swing within the channel of the cover cleat and including a projection 30 for engaging in the socket and extending at the outer end in advance of the cover.

In testimony whereof, I affix my signature in presence of two witnesses.

FREDERICK W. SCHOEN. [L. S.]
